COLLAPSIBLE CONTAINER CLOSURE

Ted Harrison, Erwin, Tenn., assignor of one-half
to A. L. Chavieourt, Erwin, Tenn.

Application October 21, 1938, Serial No. 236,313

1 Claim. (Cl. 221—60)

This invention relates to closures for collapsible tube containers used in the sale and dispensing of dental, shaving, cold creams and other similar semi-liquid materials, and has for the primary object the provision of a device of this character which will permit easy and quick removal of the closure or cap from the discharge neck of the container without becoming fully detached from said container so as to prevent loss or dropping 5 of the cap when removed or in the act of removing or replacing thereof on the container.

With these and other objects in view, the invention consists in certain novel features of construction, combination and arrangement of parts 10 to be hereinafter more fully described and claimed.

For a complete understanding of my invention, reference is to be had to the following description and accompanying drawing, in which

20 Figure 1 is a fragmentary side elevation illustrating a collapsible tube or container equipped with a closure constructed in accordance with my invention.

Figure 2 is a top plan view partly in section 25 illustrating the same.

Figure 3 is a perspective view illustrating the closure or cap mounting.

Figure 4 is a vertical sectional view illustrating the cap or closure.

30 Referring in detail to the drawing, the numeral 5 indicates a collapsible tube or container having the usual screw threaded discharge neck on which is threaded a closure or cap 6 forming a part of the present invention and consisting of 35 a substantially cone-shaped body 7 having a screw threaded socket 8 to permit the body to be threaded onto the neck of the container or tube. The body 7 adjacent the base thereof is provided with an annular groove 9 to receive a mounting 40 10 consisting of a resilient split ring 11 having the ends thereof bent to form parallel arms 12 and the latter having portions thereof bent to form L-shaped portions 13 arranged in spaced opposed relation.

45 The resilient ring 11 may be expanded to permit said ring to be passed over the body 7 of the cap or closure and to become seated in the groove 9 whereby the mounting 10 will then have the

cap or closure rotatably connected thereto. The L-shaped portions 13 of the arms 12 provide hinge pintles to be received in sockets 14 of a lug 15 formed on the container or tube 5. Through the use of the portions 13 and the lug 5 10 15 and its sockets the mounting becomes hinged on the tube or container. The cap or closure then may be swung into engagement with the neck and threaded thereon in the usual way. A portion of the body 7 of the closure or cap is 15 provided with serrations to provide a knurled surface to permit a person to readily grip the cap or closure. After the cap or closure has been threaded on the neck of the container or tube it 20 may be swung laterally of the latter still remaining attached to the container or tube and consequently preventing the loss thereof.

It is believed that the foregoing description, when taken in connection with the drawing, will fully set forth the construction and advantages 25 of this invention to those skilled in the art to which such a device relates, so that further detailed description will not be required.

What is claimed is:

A closure for the neck of a collapsible tube 25 comprising an internally threaded tubular cap for turning on and off said neck and provided with a circumferential groove in the base end thereof, an apertured lug adapted to be carried by the neck end of said tube, and a single piece 30 cap holder of resilient wire comprising a ring at one end thereof loosely fitting in said groove to provide for free turning of said cap relative to the holder, said ring being split for spreading to insert the same in the groove and having overlapping stretches for maintaining the continuity of the ring under spreading, and a pair of parallel arms extending from said stretches and terminating in rightangled ends including trunnions 35 rotatably mounted in opposite sides of said lug 40 whereby the holder is swingable in opposite directions to move the cap toward and from said neck, said ends also including stop portions at right angles to said arms and trunnions for engaging the neck end of the tube to limit swinging of 45 the holder in one direction.

TED HARRISON.
